[57] **CLAIM**

The ornamental design for a disposable trash liner with elastic bands, as shown and described.

DESCRIPTION

FIG. 1 is a top, front and right side perspective view of the disposable trash liner with elastic bands showing our new design;

FIG. 2 is a front elevational view thereof, the rear being a mirror image of the front shown in FIG. 2;

FIG. 3 is a left side elevational view thereof, the right side being a mirror image of the side shown in FIG. 3;

FIG. 4 is a top plan view thereof; and,

FIG. 5 is a bottom view thereof.

FIG. 1

FIG. 2

FIG. 3

FIG. 4

FIG. 5
